(57) **CLAIM**

The ornamental design for a cordless circular saw, as shown and described.

DESCRIPTION

FIG. 1 is a left/front perspective view of a cordless circular saw.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a left/front perspective view of a cordless circular saw.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines are for illustrative purposes only and form no part of the claimed design.
